UNITED STATES PATENT OFFICE.

WILLIAM H. WILSON, OF CYNTHIANA, KENTUCKY.

IMPROVEMENT IN HEAD-PROTECTORS FOR HORSES.

Specification forming part of Letters Patent No. 127,820, dated June 11, 1872.

To all whom it may concern:

Be it known that I, WILLIAM H. WILSON, of Cynthiana, in the county of Harrison and State of Kentucky, have invented a new and useful Improvement in Head and Face Protectors for Horses, of which the following is a specification:

Nature and Objects of the Invention.

This invention relates to an improvement in devices for protecting the heads and faces of horses while they are being shipped from point to point in cars, &c.; and consists of a longitudinal curved strap, and a transverse curved strap provided with a cushion, and a brow-band, nose-piece, and throat-latch, for securing the device to the horse's head, the whole being arranged in such a manner that one portion of the cushion will cross the neck back of the ears, and another portion will pass between the ears and eyes, and so far down the face of the horse as to fully protect him from injury by bumping his head or face while being shipped in cars, &c., as will hereinafter more fully appear.

Description of the Drawing.

Figure I is a view in perspective of the device in position upon the horse's head. Fig. II is a partial vertical longitudinal sectional view centrally through the device.

General Description.

In the accompanying drawing, A is the longitudinal strap, curved at its upper end so as fit that portion of the horse's head between and slightly in front of its ears. The strap A is provided with a slot, B, for the reception of the bump or projection on the horse's head slightly in front of the ears. C is the transverse strap, curved so as to fit the horse's neck immediately back of the ears, and provided with strings, D, for securing it to the halter. E is the brow-band; F, the nose-strap; and G,

the throat-latch. The nose-strap F and throat-latch G are connected under the horse's chin by a loop, H. The cushion I is built upon the straps A and C, and is stuffed with curled hair or any other suitable material. A base or bottom, J, is made to the cushion for the part over the slot B. The cushion I is nearly the shape of the letter T, the transverse and upright parts being curved—that is to say, it has the curved arms K K and the curved stem L. The arms K K and the stem L may be each six inches or more in length. The strap A below the termination of the stem L forms a face-piece for the device.

Operation.

The device is placed upon the horse's head, the arms K K fitting snugly over the horse's neck immediately back of the ears, and the stem L passing between the ears and eyes down the face of the horse. The slot B receives the projection on the horse's head slightly in front of its ears. The device is secured to the halter by the strings D. The nose-piece, brow-band, and throat-latch, are operated in the usual manner.

Claim.

Having thus described my invention, what I claim as new and useful, and desire to secure by Letters Patent, is—

A head and face protector for horses, composed of the strap A, provided with the slot B, the strap C, cushion I, brow-band E, nose-piece F, and throat-latch G, combined and operating substantially as hereinbefore set forth.

In testimony that I claim the foregoing improvement in head and face protectors for horses, as above described, I have hereunto set my hand and seal this 1st day of May, 1872.

WM. H. WILSON. [L. S.]
